UNITED STATES PATENT OFFICE.

JOHN W. POPE, OF DECORAH, AND WILLIAM C. MEYRICK, OF DES MOINES, IOWA, ASSIGNORS TO THE DECORAH WIND-MILL COMPANY, OF DECORAH, IOWA.

POWER-WINCH.

SPECIFICATION forming part of Letters Patent No. 614,309, dated November 15, 1898.

Application filed April 25, 1898. Serial No. 678,758. (No model.)

To all whom it may concern:

Be it known that we, JOHN W. POPE, a resident of Decorah, county of Winneshiek, and WILLIAM C. MEYRICK, a resident of Des Moines, county of Polk, State of Iowa, citizens of the United States of America, have invented certain new and useful Improvements in Power-Winches, of which the following is a description.

10 Referring to the accompanying drawings, wherein like reference-letters indicate like or corresponding parts, Figure 1 is a perspective view of our improved device. Fig. 2 is a similar view with the lever and cap removed. Fig. 3 is a central vertical section of our device. Fig. 4 is a horizontal section on line 4 4 of Fig. 3. Fig. 5 is a bottom plan of the top C, showing the ratchet connection with the drum B. Fig. 6 is a bottom plan of the 20 cap and lever seat. Fig. 7 is a perspective view of the bottom of the block.

The object of our invention is to provide a simple, efficient, and economical winch which may be utilized for trying and difficult work—25 such, for example, as stump-pulling.

To this end it is embodied in a novel construction and combination of elements shown and described, and particularly pointed out in the claims.

30 In the drawings, A represents a suitable base, B the winding-drum, and C the top of the winch or capstan. The top of the drum, extending through the top of the winch, terminates in the cam-face b, provided with shoulders b', adapted to interlock with the similar shoulders d' in the cam-face d of the locking-block D.

E is the cap and lever seat, adapted to be placed over and inclose the locking-block D. 40 The lugs e are designed to register with the groove or depression d² in the block D, Fig. 4, thus allowing the block a vertical movement within the cap without disconnecting it therefrom. The cap has at its base a projecting flange e', over which an arm or arms F, firmly secured to the top C, extends, firmly binding the cap to the top C, but permitting rotation thereon.

G is the lever or sweep, to which power may 45 be applied to operate the machine.

H is a bar or rod extending from the lever to the block D, to which it is suitably connected, and I is a cam-lever connected to the bar or rod H, by means of which the block D may be raised to clear the cam b and release the 55 lever G from connection with the drum.

K is a ratchet-lever preferably secured to the bottom of the top C and engaging with the ratchet B' of the drum to take up and retain all the advantage gained by the operation of the device.

The mode of operation is as follows: The winch being suitably secured by the anchor-rope L, secured on the standard M, or in any other preferred manner, the cam-lever I is 60 operated to bring the locking-block D into engagement with the cam top b of the drum B. The rotation of the sweep or lever G will then operate the drum B and draw on the cable wound thereon. The ratchet K takes 65 up and retains the drum in the position gained. If for any reason the sweep or lever G cannot be given a full rotation or more advantage can be gained by giving a partial revolution only, it may be reversed, when the 70 block D, being vertically movable in its cap E, as described, will ride over the cam-face b, when it will again drop into position and the lever again be rotated to operate the drum, 75 as before.

When it becomes necessary or desirable to reverse the drum B, the cam-lever I is operated to lift the block D out of engagement with the drum. The ratchet K may then be 80 released, and the drum will then be free to 85 reverse without affecting the lever G, which is then disengaged from the drum.

It is obvious, after pointing out our improvements, that minor modifications may be made without departing from the spirit of 90 our invention. Hence we do not wish to be limited to the exact construction shown, the broad idea of our invention consisting in the construction of a device of the kind described provided with a movable locking-block disconnected from the other parts of the machine and serving as an intermediate connection between the operating means within which it is inclosed and the drum, thus controlling the operation of the latter.

Having thus described our invention, what we claim as new, and desire to secure by Letters Patent, is—

1. In a winch, the combination of a base, 5 a winding-drum provided with a clutch member, an operating means for the drum and disconnected therefrom, and a movable clutch member inclosed within said operating means and serving as an intermediate connection 10 between the operating means and the drum, substantially as described.
2. In a winch, the base, the top, a winding-drum provided with a clutch top, a rotatable cap for the end of the drum, and means for 15 rotating the cap, in combination with a clutch-block adapted to engage the drum, located within the cap and movable therein to engage or disengage the drum, and means for causing the block to rotate with the cap, whereby 20 the clutch-block forms an intermediate connection between the power and the drum, substantially as described.
3. In a winch, the base, the top, a winding-drum provided with a clutch top, a rotatable 25 cap for the end of the drum and means for rotating the cap in combination with a clutch-block adapted to engage the drum, located within the cap and movable therein to engage or disengage the drum, means for causing 30 the block to rotate with the cap and means for disengaging the clutch-block from the drum whereby the block forms an intermediate connection between the power and the drum and may be engaged or disengaged 35 from the drum at will, substantially as described.
4. In a device of the kind described, the base, the top, the winding-drum provided with the clutch top and means to hold the drum 40 against reversal, the rotatable cap and means

for rotating the same, in combination with the clutch-block adapted to engage the drum, located within the cap and movable therein to engage or disengage the drum, means to disengage the clutch-block at will and means 45 for causing the block to rotate with the cap, substantially as described.

5. In a device of the kind described, the base, the top, a vertical winding-drum provided with a clutch top, a rotatable cap for 50 the end of the drum and means for rotating the cap, in combination with a clutch-block adapted to engage the drum, said clutch-block being located within the cap and vertically movable therein, means to disengage 55 the clutch-block from the drum at will and means for causing the block to rotate with the cap, substantially as described.

6. In a device of the kind described, the base, the top, a vertical winding-drum provided with a clutch top, a rotatable cap for the end of the drum, and means for rotating the cap, in combination with a clutch-block 60 adapted to engage the drum, said clutch-block being located within the cap and vertically movable therein, means for causing the block to rotate with the cap, a rod or bar extending through the cap and attached to the block, and means for lifting the rod or bar and block at will, substantially as described 70 and for the purpose set forth.

JOHN W. POPE.
WILLIAM C. MEYRICK.
